UNITED STATES PATENT OFFICE.

EMMA THOMAS FRANCISCO, OF CHICAGO, ILLINOIS.

FURNITURE.

1,295,296.

Specification of Letters Patent. Patented Feb. 25, 1919.

Application filed May 10, 1918. Serial No. 233,619.

To all whom it may concern:

Be it known that I, EMMA THOMAS FRANCISCO, a citizen of the United States, and a resident of Chicago, Cook county, Illinois, 5 have invented certain new and useful Improvements in Furniture, of which the following is a specification.

My invention relates to improvements in furniture, and has special reference to improvements in seat supports.

The object of my invention is to provide a seat support which, while being made of metal, as distinguished from woven straps or bands, shall be more or less yielding, 15 which shall be more permanent and more durable than those in common use and which shall be capable of being easily, cheaply and quickly secured in position.

A further object of my invention is to provide a seat support for furniture, particularly chairs and settees, which shall be so arranged that one size of support can be readily used for seat openings varying considerably in dimensions.

25 A further object of my invention is to provide a seat support for chairs and settees which can be easily and readily secured in position in repairing such articles.

Further objects and features of my invention will appear hereinafter.

My invention consists in a seat support for furniture preferably made of woven wire and having dimensions somewhat smaller than the seat opening to which it is to be applied, and adjustable metallic securing devices secured to the margin of the support and adapted to have their free ends permanently secured to the frame of the opening.

40 My invention also consists in the several features of construction and in the combinations and arrangements of parts and devices by means of which I am enabled to attain the above mentioned and other objects and all as hereinafter described and particularly pointed out in the appended claims.

My invention will be more readily understood by reference to the accompanying drawing forming part of this specification, and in which:

50 Figure 1 is a bottom plan view of a chair seat provided with a seat support constructed in accordance with my invention;

Fig. 2 is a vertical section of the seat on the line 2—2 of Fig. 1;

55 Fig. 3 is a sectional view similar to Fig. 2 illustrating the means of extending the con-

nectors between the support and the chair frame; and

Fig. 4 is a sectional view similar to Fig. 2, illustrating the manner of building up an elongated support for the seat of a couch or couch-back.

As shown in the drawings, my support consists primarily of a woven wire support member 1, provided with a rim, frame or edge 2 of relatively heavy wire and the cross wires 3 which extend from side to side and are secured at their ends to the frame 2 of the support. The support 1 is smaller in area than the opening 4 of the chair seat 5, 70 and I preferably secure the support 1 to the chair seat in such a manner that it is not exactly rigid therewith, but can yield somewhat to pressure.

In the form shown in the drawings, I secure the frame to the chair seat by means of hooked connecting members 6, each of which is provided with a hook 7 for engagement with one of the side bars 2 and in its opposite end with a perforation for receiving a screw or nail 8 for fastening the connector to the chair seat.

I preferably arrange several of these connectors on each side of the support and I preferably arrange them close to or in line with the cross wires, so that the strain incident to the use of the seat will not tend to distort the frame wires 2.

In the form of seat shown in the drawings I have illustrated an ordinary cushion seat 90 having coil supporting springs 9 between the support 1 and the cushion 10.

The supports 1 serve as an excellent foundation upon which to rest the springs 9 and to which the lower ends of the spring 9 can readily be secured.

A particular object of my invention is to provide a support of the character described which can be used in the repair of furniture, particularly chair seats, and as it is necessary to manufacture the supports in large quantities, it is desirable that the necessary number of sizes of supports be reduced to a minimum, and the hook connectors 6 are particularly useful in accomplishing this purpose. As shown in Fig. 3, where the opening in the chair seat is so large that the connectors 6 could not be properly secured to the chair frame, I connect on additional connectors 6 until the connectors extend far enough to be secured to the chair frame by the screws 8.

When applying my improved support to the seat of a settee 11, Fig. 4, I preferably make the support in sections, by joining together a number of the supports 1. For this purpose I connect the adjacent edges of the support 1 by wire loops 12, as shown in Fig. 4.

It will now be clear that by means of my invention, I provide a seat support, which, 10 although practically indestructible, is still yielding to a certain extent, that is, it is not as rigid as a board, and it can be readily applied to either new or old furniture. Furthermore it is particularly adapted for 15 the repair of old furniture to replace the woven straps which are now the common means of supporting the springs 9.

As many modifications of my invention will readily suggest themselves to one skilled 20 in the art, I do not limit or confine my invention to the specific structures herein shown and described.

I claim:

1. A furniture seat repair device of the 25 kind described, adapted to be applied to a furniture cushion seat frame containing supporting springs, comprising a flat, rectangular woven wire seat support member having a relatively heavy marginal wire and lighter

cross wires, substantially parallel to the 30 edges of the frame and attached at their ends to said marginal wire, the device being smaller than the opening in the seat frame to which it is to be applied, and links attached to the marginal wire at intervals and 35 at the points where the cross wires are secured, for attaching said device to the underside of the furniture seat frame without removal of the overlying springs or cushion.

2. A furniture repair device of the character described, adapted to be applied to a furniture cushion frame containing supporting springs, comprising a reticulated woven wire member, the several parts thereof each having a margin of heavier wire than the 40 body thereof, the body formed of cross wires attached at their ends to the marginal wire, said member being smaller in dimensions than the opening in the furniture frame to which it is to be applied, and links attached 45 to the outer marginal wire of the member at intervals in alignment with cross wires thereof for attaching the same to a furniture frame, without removal of the associated 50 springs or cushion.

In witness whereof, I hereunto subscribe my name this 25th day of April, A. D. 1918.

EMMA THOMAS FRANCISCO.
